HENRY R. BARNHURST, DECEASED, LATE OF CATASAUQUA, PENNSYLVANIA, BY
HENRY G. BARNHURST, ADMINISTRATOR, OF CATASAUQUA, PENNSYLVANIA.

BURNING PULVERIZED FUEL.

1,178,464.

Specification of Letters Patent.

Patented Apr. 4, 1916.

Application filed March 31, 1914. Serial No. 828,465.

To all whom it may concern:

Be it known that HENRY R. BARNHURST, deceased, late a citizen of the United States, residing at Third and Pine streets, Catasauqua, Lehigh county, State of Pennsylvania, has invented certain new and useful Improvements in Burning Pulverized Fuel; and I, HENRY G. BARNHURST, administrator of the estate of the said HENRY R. BARNHURST, do hereby declare the following to be a full, clear, and exact description of the invention, such as will enable others skilled in the art to which it appertains to make and use the same.

15 The invention relates to certain new and useful improvements in the burning of pulverized fuel, and has particular relation to the method of establishing and maintaining the necessary conditions for effective combustion for obtaining predetermined temperatures suitable for given conditions of use.

It also relates to the construction and arrangement of the means of apparatus for practising the method.

In carrying out the invention there is located within the interior of the pipe or conduit which is to deliver into the furnace chamber the combustible mixture of air and pulverized fuel, a pipe of relatively smaller diameter, which conveys and discharges into the outer pipe a current of air of high pressure which it receives from any suitable source of supply. The interior high pressure air pipe referred to discharges into the outer pipe at a point sufficiently removed from the discharge end of the outer pipe to permit the high pressure air to exercise an effective propelling effect upon the mixture of air and pulverized fuel on its way to the furnace chamber and to keep the pulverized fuel in suspension in the air mixture. To render the operation effective, the high pressure air jet discharged from the inner tube is utilized for two auxiliary and co-operating purposes, to wit,—to draw in air with the pulverized fuel as the latter is fed into the outer pipe, and to draw in air through the longitudinal annular space existing between the inner and outer pipes. Accordingly, the air provided for the consumption of the fuel is admitted at three different sources of supply, that is to say, (1) through the annular space between the

outer pipe and the inner high pressure pipe, 55 (2) through the high pressure pipe itself; and (3) through the opening which admits the pulverized fuel, said opening being in close proximity to the discharge end of the high pressure pipe, so that the entering fuel 60 with its entrained supply of air will be promptly forwarded by the injecting action of the high pressure jet into the main body portion of the outer pipe. Just before entering the zone in advance of the discharge 65 end of the high pressure jet, the mixture of air and fuel drawn in through the fuel opening will be joined by the volume of air drawn in through the annular space between the inner and outer pipes, and, finally, as 70 hereinbefore indicated, the resultant air and fuel mixture will be further augmented by the supply from the high pressure jet itself, whose propelling effect will be exercised in assuring regular, sustained and uniform delivery 75 of the ultimate mixture from the discharge end of the outer pipe into the furnace chamber or other combustion space intended.

The fuel travel provided in the practice 80 of the invention is quite short after the delivery of the fuel and its associate air into the burner pipe, and the mixture of air and fuel should enter the combustion chamber at a relatively low pressure and a relatively 85 low velocity. Consequently, this low pressure and velocity, with respect to high pressure of the central air injecting jet should prevail in the space intervening between the discharge end of the high pressure jet and 90 the discharge end of the outer pipe, while, at the same time, the conditions should be such that the pulverized fuel is sustained in the air current without danger of depositing in the pipe. These functions are 95 attained in the practice of the invention by making available the relatively high velocity and energy of the primary air jet for imparting a lower velocity and pressure to the secondary air delivery, with the resultant effect that a largely increased volume of total air of the appropriate low velocity and pressure, and having disseminated through it a practically homogeneous 100 burden of pulverized fuel will be discharged 105 into the furnace chamber.

It is, of course, important, and indeed essential, that the volume of air associated

with the fuel and passing out of the burner pipe in admixture with it, shall be capable of close control, inasmuch as the maintenance of proper temperatures within the furnace chamber is dependent upon the proportion by volume which the air bears to the fuel. In the present invention, provision is made for accurately regulating the supply of air entrained between the inner and outer pipes, by means of a regulating cone which may conveniently be sleeved upon the inner pipe and which is capable of longitudinal adjustment so as to vary the effective area of entrance of the secondary air at the air admission end of the outer pipe. By this expedient, the volume of secondary air thus admitted may be controlled with great precision, and without cutting down the pressure of the injector jet, which pressure should remain practically constant in its relation to the entrainment of the air and fuel through the fuel supply opening. It is further characteristic of the invention that it dispenses with the necessity for the employment of fans or blowers for supplying the secondary air to the burner, and that there is no constriction or obstruction in the annular space through which the secondary air supply passes.

30 In the accompanying drawing,—Figure 1 represents a longitudinal sectional view, of a pulverized fuel burner embodying the invention; Fig. 2 represents a top plan view thereof, partly in section; and Fig. 3 represents a cross-section on the line 3—3 of Fig. 1.

Similar numerals of reference indicate similar parts throughout the several views.

Referring to the drawing, 30 indicates 40 the outer tube or burner pipe, preferably of substantially oval cross-section, as indicated in Fig. 3. The burner pipe 30 may be provided with any suitable mouth piece, as 38, to direct or distribute the discharge, 45 and the directing mouth piece, if desired, may be water-cooled at 39 and 40, as shown. The burner pipe 30 is entirely open at its rear end, and receives an inner high pressure air injector pipe 32, separated therefrom by an intervening annular space and which is supplied with air from any suitable source, as, for instance, from a fan operating to supply the air at constant pressure and velocity. Slidably mounted on the 55 air injector pipe 32 is a cone 37, which may be advanced toward or retracted from the rear open end of the burner pipe 30 to regulate the effective area of the opening between the burner pipe and the air injector pipe. Pipe 32 is provided with a suitable damper or regulator 32'.

The burner pipe 30 has a fuel receiving funnel 31, above which is supported a nozzle 29, through which the pulverized fuel is 60 dropped into the burner pipe 30, in near

proximity to the discharge end of the inner pipe 32. The pulverized fuel, as, for instance, pulverized bituminous coal, is supplied to the nozzle 29 by feed apparatus, of such a character that the partial vacuum due to the intake of air at the funnel 31 shall not accelerate the feed and thus interfere with its regularity and uniformity. Thus the feed apparatus may conveniently 70 consists of a hopper 15 from which the dry pulverized coal passes through a pair of adjustable gates 16 and 17 into a housing 18 wherein a screw conveyer 19 is suitably mounted. The shaft 20 of the screw conveyer is carried at its rear end in a bearing 21, and is equipped with a sprocket wheel 22, whereby it may be driven to advance the pulverized fuel admitted from the hopper 15. At the front end of the housing 18, and preferably removable therefrom for purposes 75 of repair, is an auxiliary housing 23 at the end of which is a removable front bearing 24, wherein the shaft of the screw conveyer is journaled. An auxiliary conveyer 25 is mounted on this shaft, but is spaced from the front end of the conveyer 19 far enough to form a substantial gap 26. The blades of the conveyers 19 and 25 may be made integral with the shaft 20 or may be suitably attached thereto, and they preferably fit 80 closely within the housing with the minimum practicable amount of clearance.

In operation, the pulverized coal is carried forward by the screw flights or convolutions of the conveyer 19 until it reaches 85 the gap 26. Not being propelled forward by the convolutions at this point, the material accumulates in the gap, but, as further material continues to be delivered by the conveyer 19, the material in the gap, receiving 90 constant accretions, is pushed bodily forward upon the convolutions of the conveyer 25, which thereupon takes up the delivery of material at the same rate at which it has been built up in the gap by the convolutions 95 of the conveyer 19. The material within the gap constitutes, therefore, a dam against 100 tendency to "flood," that is to say, to accelerate the motion of the pulverized fuel in the conveyer housing.

When the blower is in action, delivering 105 air at high velocity through the pipe 32 into the burner pipe 30, there will be developed by the injector action an inflow of air through the funnel 31, so that the pulverized fuel dropping through the fuel nozzle 29 will be caught by this downwardly 110 moving air and mixed therewith. So also, secondary air will be entrained through the rear open end of the burner pipe 30, the 115 proportional amount depending upon the adjustment of the movable cone 37, and upon the velocity and constancy of pressure of the air supplied by the pipe 32. As the result of these several factors, the high-ve- 120

lacity air supplied by the pipe 32 becomes mixed with a larger volume of air drawn in through the rear of the pipe 30 and also through the funnel 31, and, with this entire 5 quantity of air, the pulverized fuel becomes intimately mixed as it is projected forward toward the delivery end of the pipe 30. By arranging the fuel supply nozzle above the air supply pipe 32, and just in the rear of 10 its delivery end, the pulverized fuel is to some extent supplied initially to air of high velocity and so is scattered across the entire cross-section of the tube, and is started toward the burner nozzle at a speed sufficient 15 to obviate any danger of deposit of the fuel in the burner pipe. But, when the mixture of air and fuel reaches the burner nozzle, said fuel and the high-velocity air which gives it impetus have become so intimately 20 mixed with the much larger volume of entrained air that the whole mixture issues from the burner nozzle at the desired low velocity. This permits the fuel to burn close to its point of admission so that the 25 surrounding wall receives the heat desirable for maintaining its prompt deflagration as it enters the furnace chamber.

By the arrangement disclosed it is possible to use a small high pressure fan and 30 yet obtain at the delivery ends of the burner pipe a large volume of low pressure air within which the pulverized fuel is properly distributed; and, by suitably adjusting the sizes of the air supply pipe 32 and the 35 burner pipe 30, it is possible to obtain at the burner nozzle the appropriate low velocity and the appropriate ratio between the pulverized fuel and the total air to correspond to the particular exigencies of use. 40 The definite provision thus afforded for predetermining the character and velocity of the entering combustible mixture, enables the operator to produce a given temperature within the furnace by correspondingly calibrating the amount and rate of fuel supply 45 to the known velocity and pressure of the air which passes through the pipe 32, and the amount of the secondary air entering at the rear open end of the pipe 30 and regulated by the position to which the cone is 50 adjusted.

It will be noted, as a further advantage of the construction, that the feature of feeding the pulverized fuel from the nozzle 29 55 through the funnel-shaped opening 31 permits the operator to observe the flow of the pulverized fuel as it issues from the nozzle, and the character of the feed, so that he can at all times determine whether it is proceeding with the required uniformity and 60 regularity.

What is claimed is:

1. Apparatus for burning pulverized fuel, comprising an outer burner pipe, open at 65 its ends, an inner high pressure air injector

pipe projecting thereinto with an annular space therebetween, means for regulating the flow of air through said inner pipe, said inner pipe serving to entrain a secondary supply of air through said annular space, 70 means for regulating said secondary supply of air, the outer pipe being provided with an inlet opening, rearwardly of the discharge end of the injector pipe, and means for dropping pulverized fuel through said 75 inlet opening; substantially as described.

2. Apparatus for burning pulverized fuel, comprising an outer burner pipe, open at its ends, an inner high pressure air injector pipe projecting thereinto with an annular space therebetween, said inner pipe serving to entrain a secondary supply of air through said annular space, the outer pipe being provided with an inlet opening, rearwardly of the discharge end of the injector pipe, 80 means for dropping pulverized fuel through said inlet opening, and a regulating cone for varying the effective area of the annular space between the two pipes; substantially 85 as described.

3. Apparatus for burning pulverized fuel, comprising an outer burner pipe, open at its ends, an inner high pressure air injector pipe projecting thereinto with an annular space therebetween, said inner pipe serving 90 to entrain a secondary supply of air through said annular space, the outer pipe being provided with an inlet opening rearwardly of the discharge end of the injector pipe, said opening having a short funnel-like rim, and a pulverized fuel feed nozzle discharging into said rim while permitting the intake of air through said inlet opening about said nozzle; substantially as described.

4. Apparatus for burning pulverized fuel, comprising an outer burner pipe, open at its ends, an inner high pressure air injector pipe projecting thereinto with an annular space therebetween, said inner pipe serving to entrain a secondary supply of air through 100 said annular space, the outer pipe being provided with an inlet opening rearwardly of the front end of said inner pipe, said opening having a funnel-like rim, a pulverized fuel feed nozzle discharging into said rim 105 while permitting the intake of air through said inlet opening about said nozzle, a conveyor housing for supplying the pulverized fuel to the nozzle, said housing being open from end to end, and conveyors within the 110 housing, for forwarding the pulverized fuel to the nozzle, said conveyors being separated by an intervening gap for the formation and maintenance of a fuel dam thereat which will protect the feed from abnormal acceleration in the housing; substantially 115 as described.

5. Apparatus for burning pulverized fuel, comprising an outer burner pipe, open at its ends, an inner high pressure air injector 120

130

pipe projecting thereinto with an annular space therebetween, said inner pipe serving to entrain a secondary supply of air through said annular space, the outer pipe being provided with an inlet opening and having a shallow funnel-like rim, a pulverized fuel feed nozzle discharging into said rim while permitting the intake of air through said inlet opening about said nozzle, and a regulating cone mounted on said high pressure air pipe for varying the effective area of the

annular space between the two pipes; substantially as described.

In testimony whereof I affix my signature in presence of two witnesses.

HENRY G. BARNHURST,
Administrator of Henry R. Barnhurst, deceased.
